Primary Examiner — Garth Rademaker*(74) Attorney, Agent, or Firm* — James J. Lillie; Lillie Law, LLC(57) CLAIM

The ornamental design for a plant stand, as shown and described.

DESCRIPTION

FIG. 1 is a front view of a plant stand, showing only the shelf portion thereof, with the remainder of the design omitted for ease of disclosure;

FIG. 2 is a rear view thereof;

FIG. 3 is a side view thereof;

FIG. 4 is a front view thereof, wherein the shelf portion is placed upside down, on its face;

FIG. 5 is a front elevational view of the plant stand, showing the full design, comprised of both a shelf portion and a chair portion; and,

FIG. 6 is a side view thereof.
